ASH REMOVER

Edward C. Lunda, Portland, Oreg., assignor to
Iron Fireman Manufacturing Company, Port-
land, Oreg.

Application June 18, 1935, Serial No. 27,190

4 Claims. (Cl. 110—45)

This invention relates generally to underfeed stokers, and particularly to ash removers therefor.

The main object of this invention is the provision of an exceedingly simple and efficient form of underfeed stoker employing the unique form of ash remover which is adaptable to manual or power driven operation.

The second object is the provision of an improved form of ash remover employing a pin hole grate surface through which air may be supplied to the fuel over a relatively large area and to which is added a means for scraping the grate surface and depositing the main body of the ashes in outlets which discharge beyond the plenum chamber.

The third object is the provision of a stoker having pin hole grates together with means for withdrawing ashes from the floor of the plenum chamber.

I accomplish these and other objects in the manner set forth in the following specification as illustrated in the accompanying drawings, in which:

Fig. 1 is a perspective view of the device showing the stoker partially broken away.

Fig. 2 is a section taken along the line 2—2 in Fig. 1.

Fig. 3 is a horizontal section taken along the line 3—3 in Fig. 2.

Fig. 4 is a section taken along the line 4—4 in Fig. 2.

Fig. 5 is a section taken along the line 5—5 in Fig. 4.

Fig. 6 is a section through the furnace showing the retort and tuyères together with the ash remover mechanism in elevation.

Fig. 7 is a section taken along the line 7—7 in Fig. 5.

Similar numbers of reference refer to similar parts throughout the several views.

Referring in detail to the drawings, there is shown the usual form of hopper 10, whose base 11 communicates by means of a coal feeding tube 12 with a retort section 13 which is surrounded by means of a circular wall 14 forming a plenum chamber 15.

Within the coal tube 12 is a worm 16 which is driven by a motor 17 through a gearing contained within the casing 18. The motor 17 also operates a fan contained within the fan casing 19 which communicates by means of an air delivery duct 20 with the plenum chamber 15.

The plenum chamber walls 14 rest upon a floor plate 21 which is held in an elevated position

upon the legs 22. The floor 21 is provided with a plurality of slots 23 through which ashes can pass from the plenum chamber 15 downwardly through the floor 21 into the ash pit 24. Extending through the floor 21 is a vertical shaft 25 on whose squared upper end 26 is riveted a wheel 27 provided with slots 28 which can be brought into register with the slots 23 when the shaft 25 is rocked. On the lower end of the shaft 25 is secured the hub 29 of a rock lever 30 provided with the upturned ends 31. To the lever 30 is attached a connecting rod 32 which may be reciprocated by means of a hand lever 33 which is fulcrumed on the standard 34, or it may be operated by power in any convenient manner.

The plenum chamber 15 is provided with a top 35 upon which rests the outside tuyère ring 36 which is provided with an annular rib 31, which in turn extends into a groove 38 in the top 35. The outside tuyère ring 36 is secured to the top 35 by means of the bolts 39. Within the outside tuyère ring 36 are placed three tuyère segments 40, whose innermost walls 41 form an extension of the top of the retort 13 and whose tops 42 are horizontal and provided with pin hole openings 43. The walls 41 are provided with air outlet openings 44 through which air flows to the incoming coal from the space 45 between the members 36 and 40. The tuyère segments 40 are secured to the outer tuyère ring 36 by means of the bolts 46.

Surrounding the outer tuyère ring 36 is the ash removing ring 47 from which inwardly project the radial arms 48 which extend almost to the inner walls 41 and rest upon the upper surfaces of the tops 42. A rocking motion is imparted to the ash removing ring 47 by the ends 31, which are attached thereto in any convenient manner. Surrounding the ash removing ring 47 and spaced therefrom for clearance purposes is the wall 49 of the ash pit 24.

The plenum chamber 15 communicates with the space 45 through the openings 50. Channels 51 are formed through the ring 36 and slots 51—A are formed in the top portions 42 through which ashes may escape from the upper side of the top 42 into the ash pit 24 without passing through the openings 43. The slots 51—A are normally covered by the radial arms 48 when the hand lever 33 is in one extreme position of travel, as determined by the stop pins 52 in the connecting rod 32 which passes through the furnace front 53, which forms a stop for the pins 52 in either direction.

The operation of the device is as follows:

Coal is being fed from the tube 12 into the retort 13 from whence it passes upwardly past the openings 44 and outwardly upon the perforated top grate portions 42 where it is burned by the air delivered from the plenum chamber 15 from whence it escapes through the openings 43. As this coal is burned to an ash over the relatively large surface presented, it is possible to perform this burning at a lower temperature than would be possible if a smaller burning area were employed and the burning were forced, in which event the incombustibles would be fused and the problem of removing the clinkers formed would increase in difficulty.

15 With my device the resulting ash is extremely frangible and collects generally in small pieces which are easily disposed of, or in larger pieces which break up as soon as they are disturbed. The removal of the ash is accomplished by rocking the lever 33 which causes the arms 48 to move around the perforated grate surface 42 and carry the loose ash to the slots 51 which are uncovered by such movement of the arms 48.

20 While the majority of the ashes will be removed through the slots 51 into the ash pit 24, a small proportion thereof will fall through the pin holes 43 and pass through the openings 50 onto the floor plate 21 from whence they are discharged into the ash pit 24 by the rocking of the wheel 27, which occurs simultaneously with the movement of the arms 48.

25 What I claim as new and desire to protect by Letters Patent of the United States is:

1. In an underfeed stoker, the combination of 30 a retort section, an ash pit under said retort section, a tuyère section mounted on said retort section, said tuyère section surrounding the opening in said retort section, said tuyère section having a substantially flat perforated top, means 35 for supplying air to the perforations in said top, an ash removing ring capable of partial rotation about said tuyère section, and means for effecting said partial rotation, said ring having a plurality of radial arms extending toward the center 40 thereof and disposed above said perforated top, said tuyère section having ash ducts communicating with its upper side and said ash pit, said arms normally covering said ash ducts to prevent the passage of unburned fuel and gas there- 45 through while the stoker is being operated.

2. An ash remover for underfeed stokers consisting of a circular perforated grate surface including means for feeding coal upwardly through the center thereof, an ash pit under said grate surface, said grate surface having a plurality of ash discharge openings formed therein, ducts communicating with said ash discharge openings and said ash pit, an ash removing ring surrounding said circular perforated grate surface, a plurality of radial arms projecting inwardly from said ash ring and disposed above said perforated grate surface and means for imparting a relative oscillating motion between said ash removing ring and grate section whereby said arms will cover said discharge openings in one position and leave same uncovered in another position.

3. An underfeed stoker having in combination a retort having an enclosing wall spaced therefrom to form a plenum chamber, an ash pit 20 formed around said wall, an outer tuyère ring mounted on said wall and having a circular outermost portion, sectional tuyère elements disposed inside of said outer tuyère ring, the innermost portion of said tuyère elements forming an extension of said retort and having air outlet openings formed therein, the upper portion of said tuyère elements being substantially horizontal and perforated for the purpose of permitting air to flow from said plenum chamber upwardly to fuel resting upon said perforated surface, a circular ash removing ring surrounding said outside tuyère ring, said ash removing ring having inwardly extending arms within the upper edge thereof disposed above said perforated surface, and means 25 for imparting an oscillating movement to said ash removing ring, ash delivery ducts formed in the horizontal portion of said tuyère elements and said outer ring and extending from said perforated surface through said outer ring into said 30 ash pit, said inwardly extending arms normally covering said ducts and being capable of movement from one duct to the next adjacent duct in a manner to cause said arm to scrape over the perforated surface and move ashes therefrom into 35 said ducts.

4. The apparatus described in claim 3 together with means for removing ashes from said plenum chamber.

EDWARD C. LUNDA.
